UNITED STATES PATENT OFFICE.

WILLIAM W. TREVOR AND FRANCIS N. TREVOR, OF LOCKPORT,
NEW YORK.

STEAM-BOILER.

SPECIFICATION forming part of Letters Patent No. 687,413, dated November 26, 1901.

Application filed June 6, 1901. Serial No. 63,426. (No model.)

To all whom it may concern:

Be it known that we, WILLIAM W. TREVOR and FRANCIS N. TREVOR, citizens of the United States, and residents of Lockport, in the county 5 of Niagara and State of New York, have invented new and useful Improvements in Steam-Boilers, of which the following is a specification.

This invention relates more especially to 10 low-pressure boilers which are used mainly for heating buildings by steam or hot water.

The main object of our invention is to provide a large fire-space and large heating-surfaces without complicating the construction 15 or greatly increasing the cost of manufacture; and to that end we associate with an upright boiler, which contains the fire-chamber, a secondary return-flue boiler in such manner that the hot products of combustion pass from the 20 primary boiler through the return-flue boiler and escape from a smoke-box which is arranged between these boilers.

Another object of our invention is to provide the smoke-box between the two boilers 25 with means whereby the hot products of combustion can be made to pass directly from the primary upright boiler to the smoke-pipe when a direct draft is required—as, for instance, in starting the fire or for cleaning—or 30 can be made to pass through the secondary boiler before reaching the smoke-pipe for fully absorbing the available heat in the gases when the boiler is working normally.

A further object is to extend the fuel-magazine of the boiler downwardly and to surround the lower end of the magazine by a water-space for protecting the lower end of the magazine against excessive heat and for increasing the heating-surface.

40 In the accompanying drawings, Figure 1 is a vertical sectional view through a boiler embodying the invention. Fig. 2 is a horizontal sectional view substantially on line 22, Fig. 1.

Like letters of reference refer to like parts 45 in both figures.

A represents the outer cylindrical shell of the primary upright boiler, B the inner shell, which extends from the lower end of the outer shell to the top of the combustion-chamber b, 50 and b' the annular water-space between the shells. The latter are secured together at

their lower ends and spaced apart in any usual manner—for instance, by a spacing-ring a.

c is the fire-door opening, formed in the front 55 side of the upright boiler in the usual way and surrounded by the usual spacing-frame c', secured between the shells.

c² is the fire-door.

d is the opening for the exit of the smoke 60 and other hot products of combustion, arranged in the rear side of the upright boiler near the top of the combustion-chamber and surrounded by a spacing-frame d', secured between the shells. 65

E represents an annular upper head, which is secured in any approved manner to the upper end of the outer-shell A.

F is a depending inner or lower head, which is secured to the upper end of the inner shell B. 70

G is the fuel-magazine, which is preferably cylindrical and is secured at its upper end in the upper head and at its lower end in the lower head. The latter has substantially the form of an inverted-cone frustum and extends from the upper end of the inner shell B downwardly and inwardly to the lower end of the magazine. This head forms an annular water-space around the lower portion of the magazine, whereby the magazine is protected against the destructive effect of the heat in the combustion-chamber and also furnishes a very efficient heating-surface of considerable area. This permits of the magazine being extended to a considerable depth 75 into the combustion-chamber without danger to the magazine, thereby increasing the height of the magazine and its storage capacity materially. The magazine by connecting the heads also adds to the strength and 80 rigidity of the structure. A desirable manner of connecting the magazine to the two heads is by screw-threading the ends of the magazine and screwing the same into internally-screw-threaded flanges e and f on the 85 heads.

h represents the cover of the magazine.

I represents the ash-box, of any suitable construction; i, the door thereof; J, the grate, and j the fire-pot. The latter may be made 100 of fire-bricks, iron blocks, or the like, resting against the inner face of the inner shell, and

may be supported upon a flange j' . The fire-pot may, however, be omitted in small boilers and the fuel be placed directly against the inner shell.

- 5 K represents the secondary boiler, which is a return-flue boiler and arranged in rear of the primary upright boiler, so as to receive the hot gaseous products of combustion from the latter. k represents the horizontal cylindrical shell of this secondary boiler; k' k^2 , the end heads or flue-sheets; k^3 , the lower direct flues; k^4 , the upper return-flues; k^5 , the smoke-chamber at the rear end of this boiler, and k^6 the door of this chamber. The secondary boiler is placed at such a height relative to the upright boiler that the water-level, which is the same in both boilers, stands at the proper height above the flues in the secondary boiler.
- 20 m represents a water-circulating pipe connecting the lower portion of the water-space of the secondary boiler with the water-leg of the primary boiler, and m' represents a steam-circulating pipe connecting the steam-spaces of both boilers.
- 25 Between the primary and secondary boilers there is arranged a smoke-chamber N, which is composed of two compartments N' N². The compartment N' forms a connecting-passage 30 between the smoke-exit d of the primary boiler and the direct flues k^3 of the secondary boiler, and the compartment N² forms the exit-passage for the return-flues k^4 of the secondary boiler. This intermediate smoke-chamber is conveniently formed by a shell of approximately cylindrical form having about the same diameter as the return-flue boiler and is secured to both boilers in any suitable way. The two compartments N' N² are preferably formed by dividing this intermediate smoke-chamber by a diaphragm n, which is preferably arranged horizontally, so that the compartment N' is located below and the compartment N² above said diaphragm, although different arrangements may be employed, if desired. The diaphragm n is preferably provided with a draft-opening n', which can be opened or closed by a damper n². The com-

munication between the compartments N' N² is opened or closed by opening or closing the 50 damper n². When the damper is open, the draft passes directly from the combustion-chamber of the primary boiler through both compartments N' N² of the intermediate smoke-chamber to the smoke-exit n³ of the 55 compartment N² and the smoke-pipe n⁴, thus furnishing a strong draft for urging the fire and cutting out the secondary boiler when the flues of the latter require to be cleaned. When the damper is closed or when no opening is formed in the diaphragm, the draft passes from the primary boiler through the lower compartment N', the lower direct flues 60 k^3 , the rear smoke-chamber k^5 , the upper return-flues k^4 , and the upper compartment N² 65 to the opening n³, leading to the smoke-pipe, thus utilizing the secondary boiler for absorbing the available heat in the hot products of combustion which escape from the primary boiler.

70 O is a door or damper in the bottom of the intermediate smoke-chamber for removing cinders, ashes, &c.

We claim as our invention—

The combination of a primary upright 75 boiler, a secondary return-flue boiler, an intermediate smoke-chamber secured to both boilers and provided with a horizontal diaphragm which divides the smoke-chamber into a lower and an upper compartment, a 80 smoke-pipe on said upper compartment, the lower compartment connecting the smoke-exit of the primary boiler with the direct flues of the secondary boiler and the upper compartment connecting the return-flues with 85 the smoke-pipe, a direct-draft opening formed in said diaphragm, and a damper controlling said opening, substantially as set forth.

Witness our hands this 4th day of June, 1901.

WILLIAM W. TREVOR.
